UNITED STATES PATENT OFFICE.

LORENZO D. HAWKINS, OF STONEHAM, AND ERASTUS WOODWARD, OF SOMERVILLE, MASSACHUSETTS, ASSIGNORS TO JOSEPH DAVIS, BENJ. F. SPINNEY, AND CHARLES A. COFFIN, ALL OF LYNN, MASS.

BUTTON-SETTING MACHINE.

SPECIFICATION forming part of Letters Patent No. 298,200, dated May 6, 1884.

Application filed May 15, 1883. (No model.)

To all whom it may concern:

Be it known that we, LORENZO D. HAWKINS, of Stoneham, and ERASTUS WOODWARD, of Somerville, county of Middlesex, State of Massachusetts, have invented an Improvement in Button-Setting Machines, of which the following description, in connection with the accompanying drawings, is a specification, like letters on the drawings representing like parts.

This invention has for its object the production of an automatically operating machine, whereby separate buttons and separate fastenings to secure the buttons to a boot or shoe or other article, material, or fabric may be presented to the said boot or shoe or other article in correct position to enable the fasteners to be automatically driven through the material and to be curled or clinched through the medium of an anvil or clinching-surface about the eye of the button, so as to secure the same to the said article.

In the machine illustrated in the accompanying drawings, as embodying one practical form of this invention, the buttons are placed in a suitable recess or hopper, from which they pass into a button-conducting chute or roadway, along which, to the delivery end of the same, the said buttons travel by reason of their own weight or gravity, and are finally presented with the flat side of the shank and eye in a predetermined position to enable the said eye to be entered by the point of a fastener, the latter being presented in proper position with relation to the delivery end of the button-conducting chute by means of a fastener conductor or chute. The fasteners employed, as herein shown and as will be preferably used, are composed of tacks having a single prong and a head; but it is to be understood that any other well-known and suitable form of fastener adapted to be driven and clinched may be used instead with proper changes in the fastener conductor to adapt it to the particular fastener to be used. These fasteners are first placed in a suitable receiver or hopper in communication with a fastener conductor, chute, or roadway, into which latter the fasteners are fed, either by jarring or swinging the hopper in usual manner, and

along down which the said fasteners move by their own weight and gravity. The endmost fastener at the delivery end of the fastener conductor, chute, or roadway is acted upon at the proper time by a fastener carrier or transerrer, herein shown as a slotted bar working at substantially right angles to the said chute or roadway, and engaging and transferring the fastener next to be driven into proper position with relation to the driver to strike it, and also with relation to the location of the eye of the button-shank, so that the fastener, when driven through the material to which the button is to be attached, will correctly enter the said eye. Co-operating with the said driver is an anvil-block or clinching-surface, located opposite the eye of the shank and at the side of the said shank opposite the side thereof which is next to the driver, so that, as herein shown, the point of the fastener, after passing through the material, enters the center of the eye, meets the anvil or clinching-surface, and the latter causes the point of the said fastener to be curved or turned outward and back down and about the shank of the said eye; but it will be understood that the anvil or clinching-surface may be so placed and shaped that the point of the fastener will strike against it just outside the eye and be curved over the shank and down through the eye, as in United States Patent No. 247,032, and the shoe or other article or material in which the fastener is driven is at that time held between the under side of the button conductor, chute, or roadway and a yielding presser, herein shown as held pressed against the said material by a spring and adapted to be drawn back or away therefrom by a cam. The presser is adapted to be reciprocated in guideways formed on a fixed part of the frame of the machine, and the button-chute is also fitted to the said part of the frame-work; but the driver, anvil, or clinching-surface and fastener chute are mounted upon a swinging frame, so that after a fastener has been driven, and before it is released from pressure between the driver and the anvil, the said frame is swung about its center, to thus draw the button out from the holding and directing groove in the said chute, and, at the same time the

- said frame is swung sufficiently far to insure the feeding of the material for the requisite distance to properly space the said buttons, thus placing them at the proper distance apart.
- 5 The fastener to be driven, when transferred from the chute into position in line with the driver, is acted upon by the latter; but before the point of the fastener reaches the material the said fastener is made to pass between the 10 jaws of a centering device mounted upon the upper end of a slide-bar, and projected from one side of the latter so as to be in line with the driver, the said centering device acting to guide and direct the point of the fastening device into the exact position desired with relation to the eye of the button-shank and the anvil or clinching-surface. The point of the fastener having been placed under the control of the centering device, the latter commences to rise 15 in unison with the driver until the upper end of the centering device meets the material, when the said device stops and the driver continues to move and completely drive the fastening, the centering device having yielding jaws, whereby the head of the fastening device may be driven out through the said jaws, the latter being acted upon by suitable 20 springs.
- The machine herein described has been provided with means whereby, in case a fastening fails to be presented to the transferrer to be carried from the chute to the driver, the apparatus cannot act to feed the material and remove from the groove of the chute the button which should have been attached at the last operation of the driver, but which was not attached by reason of the failure of a fastener to arrive in proper position opposite the driver.
- 25 Figure 1 is a right-hand side elevation of a machine embodying this invention. Fig. 2 is a front elevation thereof. Fig. 3 is a plan or top view. Fig. 3^a shows the cam-grooves of the hubs developed. Fig. 4 is a left-hand side elevation of the swinging frame or part of the machine. Fig. 5 is an end view of Fig. 4, looking at it from the right. Fig. 5^a is a section of the fastener-chute on the dotted line y y. Fig. 6 is a detail showing part of the 30 mechanism instrumental in producing the feed. Fig. 7 is a plan view of Fig. 6. Fig. 8 is a front view of Fig. 7. Figs. 9 and 10 show in side elevation and plan the button receiver or hopper and its connected chute or conductor; Fig. 11, a section of Fig. 10 on the dotted line x x; Fig. 11^a, a section on the dotted line y' y'; Fig. 12, a rear elevation of Fig. 9. Fig. 13 is a detail with the mouth or funnel of the receiver cut off, the top plate 35 of the receiver being considered transparent, so as to represent the agitator and the shelf upon which the agitator places the buttons, the cover of the chute being partially broken out to show the roadway or groove down and along which the buttons roll or slide. Fig. 14 is a section of Fig. 13 on the line x' x'. Figs. 15 to 19, inclusive, are de-
- tails, to be referred to, of the button-chute, anvil, driver, and presser, the said figures showing how a fastener is inserted through the material into the eye of a button and clinched. Fig. 20 is a detail in elevation of the presser-foot and means for operating it. Fig. 21 is a section of Fig. 20 on the dotted line x^a. Fig. 22 is a plan of Fig. 4, with part of the anvil-lever removed. Fig. 23 is a section of Fig. 4 on the dotted line x^b. Fig. 24 shows one of the fasteners separately; Fig. 25, a detail of the fastener-transferrer.
- The main shaft A of the machine, supported in suitable bearings of the frame-work A', has placed loosely upon it a driving-wheel, A^a, the hub of which is provided with an annular groove, a, which receives the fork a' of a shipper, A^b, adapted to slide on a guide, A^c, forming part of the main frame A', the said shipper being moved in one direction by the spring A^d, and in the opposite direction by the cam A^e, fast on the main shaft A, the side of the said cam working against a pin, A^f, under the control of a treadle, the said cam and spring A^d operating in conjunction with the pin A^f, under the control of the operator, to insure the engagement of the clutch parts of the pulley and cam to drive the main shaft A, or to disengage the parts and leave the shaft at rest, so that the machine will stop itself automatically, and at a certain definite position of the main shaft whenever the pin A^f is permitted to rest. At its opposite end the 40 shaft A has a bevel-gear, B, which engages a bevel-wheel, B', on a vertical shaft, B^a, having suitable bearings, B^b, held in hubs a' of a swinging frame, B^c, by set-screws B^d. The lower hub of the swinging frame rests upon a bearing, a^e, fixed with relation to the main frame A'. The top of the gear B' is provided with a cam-groove, 100, which receives in it a roller or stud at the end of an arm, B^e, of a rocker-shaft, B^f, having suitable bearings in the frame-work, and having a second arm, B^g, which is adapted to strike the inclined face 2 of a projection, C, of the feed-controlling device, shown as an elbow-lever, C', having its fulcrum on a bolt, C^a, attached to the swinging frame B^c, the arm C^b of the said elbow-lever being normally held in the position shown in Fig. 6 by the spring 99, so that the end of the arm C^b rests against the rear end of the detector b. (Shown best in Fig. 7.) The rock-shaft B^f and its arms constitute what we shall call the "feed-lever," and it has a feed-adjusting device, b^a, the position of which on the said feed-lever may be varied and determined by the screws or adjusting devices b^b b^c. The farther the end of the adjusting device b^a is from the said lever the greater the feed, and vice versa. The face 2 of the projection C is in the radius of the shaft B^f, so as to avoid sliding friction between the said face and the feed-adjusting device b^a, while the latter, by pushing against the said face 2, causes the swinging frame to be vibrated against the stress of the spiral spring b^d; but the feed-lever cannot strike the 45 50 55 60 65 70 75 80 85 90 95 100 105 110 115 120 125 130 135

projection C' unless the head of the fastener *c* (supposed to be a tack, such as shown separately in Fig. 24) has been forced through the delivery-channel 4, which intersects the groove 5 or way 5 of the fastener conductor or chute D', and in its passage has acted against the finger 6, (shown in dotted lines, Fig. 7,) projecting from the lower end of the sleeve of the fastening-detector *b*, the said detector being held in place by a screw, *c'*, which serves as a fulcrum for it, the said detector being acted upon by a spring *c''*, which normally keeps the said finger 6 in the roadway and in the path of the head of the fastener, and this detector will be 5 operated, as will hereinafter be described.

The shaft B² has a cam-hub, D², which receives a roller or stud of the anvil-carrier D³, (shown as a lever pivoted at D⁴), the said carrier being provided at its forward end with a 20 suitable groove to receive the anvil D⁵, having a clinching-surface, 8, (see Fig. 4,) against which the end of the tack or fastener strikes and is curved, curled over, or clinched, as represented in Fig. 16, where a fastener and 25 its head are shown in white, the said fastener being inserted in the material 10 of a boot or shoe or other article, the button being marked 12. The anvil has a prong, 9, to enter the eye of the button-shank, center it, and, as will 30 be hereinafter described, assist in feeding the button out of the guideway of the button chute or conductor E. The anvil is made longitudinally adjustable in a groove on the carrier, and abuts at one end against an adjusting-screw, 13, held in a cap, E', which acts as a 35 clamp to hold the anvil in place, the said cap being forced down on the anvil by a screw, 14. The carrier D³ has a link, E², attached to it and to a radius-bar, E³, pivoted at E⁴ on 40 a part of the swinging frame B⁴. The lower end of the said radius-bar is shown as forked to embrace a block, 16, on a stud or bolt, 15, the latter being connected with a dovetailed slide, E⁵, fitted into a dovetailed groove made 45 in the frame B⁴. The slide E⁵ has attached to it by bolt 17, (see Fig. 7,) in an adjustable manner, the fastener transerrer or carrier F, the forward end of the latter being entered into the groove or way 4, before referred to, 50 the said transerrer being provided with a longitudinal slot, 18. (Shown in Fig. 25, and in dotted lines, Fig. 4.)

The fasteners *c*, dropped into the receiver or hopper F', pivoted at F² and slotted at its 55 front end at 19, (see Fig. 5,) are permitted to pass out through the said slots into the groove 20, having the cross-section shown in that detail, Fig. 5^a, where it will be seen that the groove is L-shaped, so that the enlarged, circular head of the fastener *c* is guided in the horizontal part of the said groove, while the prong part stands in the vertical part of the groove with its point uppermost. The fasteners travel down along the groove 20 of the 60 said chute or conductor, the lower end of which is curved, as best shown in Figs. 8 and 22, and the endmost fastener stops (when the trans-

ferrer F is drawn back) against the abutment or wall 23, forming part of the said chute, as shown by the black dots in Fig. 22, which latter in the groove 20 are intended to represent the shanks of the fasteners *c*. As the transerrer is moved forward from the position, Fig. 22, its end strikes against the edge of the head of the fastener and pushes the said fastener along in the groove or way 4, placing the said head in position just immediately above the driver G, which is fitted into a slot at or near the end of the chute or conductor D', as shown in Fig. 7. As the transerrer moves the fastener along in the said groove 4, the head of the said fastener strikes the finger 6, and in its passage beyond the said finger turns it and the detector *b* about its center *c'*, so that the end 24 thereof extends into the groove in the 85 transerrer F, and the shoulder at the end of the said groove acts to further turn the detector, so that its rear end swings in the direction of the arrow thereon, Fig. 7, far enough to cause the said detector to act against the 90 arm C² of the feed-regulating lever, and turn it about its center C² far enough to place the projection C at its rear end in line with the forwardly-moving feed-lever B⁶ B⁷ B⁸, as described, where it is locked by the engagement 95 of the end 24 and the slotted end of the transerrer, while the feed-lever, by its part b², acts against the projection C, and causes the swing-frame B⁴ to be moved or vibrated for the necessary distance. If a fastener should fail to 100 arrive in proper position in front of the transerrer, as the latter is moved forward, the finger 6 would not be acted upon and moved, because it can be moved only by the head of a fastener, and consequently the detector would 105 not be moved so that its end 24 will be caught in the slot of the transerrer, and hence the detector will not be turned to operate the feed-regulating lever, and the feed-lever, as it is moved forward, will not strike the projection 110 C, and the swinging frame will not be moved, and the feed of the material will not take place, nor will the button which was to be fastened by the tack which failed to come into position be withdrawn or thrown out of the button-chute. The cam G', also fast on the shaft B², receives in its groove a stud or roll of a lever, G², mounted on a movable fulcrum-pin, G³, held in ears of a short lever, G⁴, pivoted to the frame B⁴ at G⁵, the outer end of the said 120 lever G⁴ being attached to a lifting-spring, G⁶, the extent of upward movement of the lever G² being regulated by a suitable stop, G⁷, attached to the frame B⁴. The forward end of lever G² is forked or otherwise shaped to engage a suitable projection, e, from the driver-bar e', to which the driver G is attached by a set-screw, 26. The cam G', during each rotation, acts by the link H, attached to the rear end of the receiver F', to raise and lower the 130 said receiver or turn it about its pivots F², thus constantly agitating the fastenings and insuring their movement, a few at a time, out from the said receiver into the groove 20 of

the receiver, conductor, or chute D', and also it will be noticed that the said lever G' at the same time acts to reciprocate the driver-bar and driver.

5 Provision has been herein made to accommodate the stroke of the driver to the thickness of the material, and this is accomplished through mounting the lever G' on a movable fulcrum; and on inspection of Fig. 4 it will be 10 understood, when the end of the driver-bar or a shoulder thereon meets the lower end of the centering device or throat N, that the further movement of the driver-bar will be arrested, provided the upper end of the centering device or throat rests against the material, and 15 during the further movement of the rear end of the lever G' by the cam G' the fulcrum G' descends without lifting the driver, and consequently we are enabled to impart to the driver 20 a variable throw, so that the extent of the curve in the body of the fastener is more or less as the material is thin or thick. The driver will be permitted to end its driving-stroke short of the end of the centering device 25 or throat, such distance being usually a little more than the thickness of the head of the fastener, in order that the said head, under all thicknesses of material, will occupy the same 30 position with relation to the material, and by adjusting the length of the driver or its bar, so that its end will fall more or less short of the material, the fastener may be driven less or more.

35 The buttons, in quantity, are dropped into the funnel H², from which they issue into the hopper or receiver H³, made as a circular box, the bottom of which is set at an incline or tipped downward toward the front of the machine, and which contains within it the button-agitator H⁴, (shown as a disk or hub having brushes or arms 28.) The hub of the agitator is mounted at the upper end of a shaft, H⁵, extended upward through a hub, H⁶, below the bottom plate, H⁷, of the hopper or receiver. The shaft H⁵ has a gear, M, which is driven from a gear, M', fast on shaft B², through an intermediate, M'. The bottom plate, H⁷, is herein shown as constituting a part of the under-plate, 27, of the button chute or conductor E. This plate 27 has a rounded groove or channel, 30, extended from the receiver to the delivery end of the said chute, and communicates at its upper end with the said receiver H³, so that buttons may enter the said 45 groove and roll or slide along the same to the delivery end of the chute. Inside the receiver, and next to one of its circular walls, there is placed a grooved bridge or race, g, upon which the buttons are raised by the arms of the agitator, so that their heads, resting next the inner wall of the receiver, as shown in dotted lines, Fig. 13, roll along in the said race, the shanks of the buttons projecting toward the center of the said receiver. The agitator 55 sweeps the buttons along the race g, and from the end of the latter, which is extended through the outlet 29 of the receiver into a pocket at

the said outlet, as best shown in Fig. 14, the heads of the buttons then entering the groove 30 of the under plate, 27, along down which 70 groove the said buttons roll until they arrive at a point near the delivering end of the said button-chute.

75 In Fig. 11 it will be seen that the under plate, 27, is the widest along the straightest part of the chute, and by such construction the button-shank is kept horizontal, and the button is free to roll, because it stands on its edge; but as the button reaches the lower curved end of the chute the top plate of the 80 chute is made the widest, (see section, Fig. 11^a,) and the groove in it is a little wider or larger than the groove in the under plate, 27, and consequently the button is permitted to tip over so that its shank points downward at an angle 85 of about forty-five degrees and bears upon a knife-edge at 32, at which point the under plate, 27, forms a rest or support for the button which is being attached to the shoe or other article. The endmost button of the series of 90 buttons, with the open part of the eye uppermost, will be arrested by a yielding stop, 33, (see Figs. 10 and 17,) and exactly at its proper 95 position with relation to the driver and anvil, so as to insure the entrance of the prong 95 into the eye of the button as the carrier D' is turned in the direction of the arrow on it, Fig. 4.

100 The centering device or throat N, attached to the upper end of the bar N² by a screw, 34, is composed of a head provided with two spring-held jaws, 35 36, pivoted at 37, (see Fig. 22,) the spring 38, acting thereon, being held by a screw, 39, inserted in said head. The bar N² is acted upon by the spring N³, 105 one end of which is connected with a bolt, N⁴, attached to the frame B¹, and its other end with a pin, N⁵, extended from the said bar through a slot, N⁶, (see Fig. 4,) in the swinging frame B¹, and consequently the upper end 110 of the centering device or throat is self-adapting to the thickness of the stock; but the said bar N² is drawn down by the lever O, pivoted to the frame B¹ at O', the said lever having a 115 stud or roll to be acted upon by the one-sided cam O², fast on the shaft B².

120 The driver-bar e' is held in its groove by the dovetailed gib p, it in turn being held in place by screws p'.

125 The under side of the under plate, 27, of the chute E serves as a support for the material upon which the button is to be set as the centering device or throat strikes the said material. The material is held up against the said support by the presser-foot P. (Herein shown as inverted from the position commonly occupied by presser-feet in sewing-machines.) This presser-foot P has a throat, P', which is entered by the centering device or throat of the fastener, and is attached to a presser-bar, P², extended through guides P³, forming part 130 of the rigid frame A', the said bar passing through a spiral spring, P⁴, which has its lower end rested on a projection, P⁵, of the frame

A' , the upper end of the said spring receiving against it a collar, P' , adjustably attached to the said bar, the said spring acting normally to elevate the said presser-foot, and cause it to clamp the material 10 against the support referred to, as shown in Fig. 16. The presser and its bar are moved automatically to release the material 10 and to permit it to be fed by a lever, P'' , pivoted at 36, forked at one end to embrace a stud or block, P^3 , of the said bar, and having at its other end a roll or stud to be acted upon by the cam O^2 , before described, but by a portion of the said cam at the rear side of the shaft B . To depress the presser for the introduction or removal of the material, the presser-rod is extended below the frame-work A' , as in Fig. 2, and has joined to it a link, r , supposed to be attached to a treadle or foot-piece. The swinging frame is normally held against the back stop, R , (shown as a bolt,) by the spring b^5 . Having introduced the material 10 between the support and presser-foot, as described, and a button having arrived against the stop 33, the pin A' is depressed to permit the clutch portions of the driving mechanism to come together and start the machine. The carrier is moved to introduce the prong 9 of the anvil into the eye of the shank, and place the clinching surface 8 opposite the said eye, and at the same time the transerrer F is moved forward to carry the fastener into position above the end of the driver G . When the head of the fastener is thus placed above or in line with the driver, the point of the said fastener is just below the contiguous ends of the spring-held centering device or throat, and the upward movement of the driver causes the point of the fastener to be moved up between the contiguous ends of the jaws of the said centering device, the latter then being at rest a short distance from the under or wrong side of the material, after which the centering device and driver move in unison toward the material, and the centering device, striking the material, through the throat P^2 , is stopped thereby; but the driver continues to operate against the head of the fastener, and drives its point through the material and against the clinching surface 8 of the anvil, causing the point of the fastener to be curved or curled or clinched over so as to inclose the wire of the shank of the button, the driver stopping automatically in its driving movement, preferably just before its end arrives opposite the end of the centering device, as described. As the fastener is being clinched to secure the button in place, the presser-foot is automatically lowered by the cam O^2 to release the material sufficiently to permit the same to be fed, which is done as soon as the fastener is clinched by the feed-lever or its part b^2 striking against the projection C , it causing the swinging frame B^4 to be turned about the shaft B , thus carrying the anvil, driver, and tack-chute D' away from the delivery end of the button-chute E ; and the prong 9 being in the eye of the button-shank, the latter is drawn from the groove of

the button-chute past the spring-stop 33, and the material clamped between the centering device and the end of the anvil D^6 is moved far enough to place under the then endmost button of the button-chute that portion of the material which is to receive the next button; and just before the centering device and anvil release the material, to enable the frame B^4 to be swung back into its normal position by the spring b^5 , the presser-foot is elevated by the spring P^6 , to clamp the material so that it cannot be displaced until the next button has been set. If the fastener fails to be delivered properly to the driver, the feed-lever in its movement fails to strike the projection C , and the material is not fed, and the button remains in the button-chute with the prong 9 in the eye of the shank, and is not fed. In order to keep a record of the number of buttons set by the machine, the latter will be provided with a counting mechanism. (Shown in Figs. 1 and 22.) This counter is shown as a box, 97, within which, as usual, are several gears and pinions, making a train to drive a pointer, 90, over a scale, the main ratchet 96 of the train being engaged by a pawl, 95, attached to the hub of the swinging frame B^4 , the said pawl acting to turn the said ratchet one step at each return movement of the frame. The box of the counter is attached to the fixed frame A' .

We have herein shown a button conductor or chute, an anvil, a fastener conductor or chute, and a driver, and a transerrer to transfer a button from its conductor to the driver to be driven; but we do not herein claim either of the said devices separately or the combination of the said devices two or more with each other, as the same are made the subject-matter of claims in our application No. 105,910, filed September 8, 1883, to which reference may be had.

We claim—

1. In a machine for setting buttons, an independent anvil and a rest to hold the button in position with relation thereto, combined with an independent driver, and a centering device to direct the tack with relation to the anvil and eye of the button, substantially as described.

2. In a machine for setting buttons, a grooved button-conductor or chute, down which the buttons are free to roll, the said conductor having an edge, 32, to enter the angle between the back of the button and the junction of the shank therewith, substantially as described.

3. The button conductor or chute, anvil, against which to clinch the fastener, a fastener conductor or chute, and an upwardly-moved driver, combined with a transerrer to transfer a fastener into position above the driver, with its point uppermost, and with a centering device for the fastener, to operate substantially as described.

4. The button conductor or chute composed of the under plate provided with a groove

- and the top plate also provided with a groove, the under plate being of diminishing width outside the groove therein toward the delivery end of the said chute, whereby the button 5 is permitted to roll along a portion of the said chute and to then arrive in position at the thin edge 32 of the eye of the button in position to be entered by the fastener, substantially as described.
- 10 5. The button conductor or chute and the anvil, and means to carry it, combined with the presser-foot, to clamp the material while the button is being set, substantially as described.
- 15 6. The button conductor or chute and the anvil provided with a prong to engage the shank of the button, combined with a driver to direct the fastener, and with means to change the position of the anvil and driver 20 with relation to the end of the button conductor or chute to enable the button to be removed from the button-conducting chute, substantially as described.
- 25 7. The button conductor or chute, and an anvil on which to clinch or curl the point of the fastener, combined with a driver to drive the fastener and with means to operate the same and change the relative position of the said driver and button-chute horizontally, to 30 remove the button from the chute holding it, substantially as described.
- 35 8. The fastener conductor or chute, and transerrer to carry a fastener to the driver, and a driver and support for the face of the material, and an anvil having a clinching-face, combined with a centering device or throat adapted to direct the point of the fastener to the anvil to clinch the said point about the shank of the button, substantially as de- 40 scribed.
- 45 9. In a button-setting machine, a rest for the button and an adjacent anvil, a driver to drive a fastener, and an interposed device adapted to receive the point of the fastener and present it to the material, and yield to the 50 passage of the fastener between it as the latter is driven by the driver, substantially as de- scribed.
- 55 10. In a machine for setting buttons, an anvil having a clinching-surface, combined with a driver and means to automatically vary its stroke or movement, according to the thickness of the material, substantially as de- scribed.
- 60 11. In a machine for setting buttons, an anvil and a driver and a centering device or throat to control the presentation of the point of the fastener to the said anvil, and with a lever having a movable fulcrum and adapted to operate the driver, substantially as de- scribed.
- 65 12. In a machine for setting buttons, a fastener conductor or chute, a transerrer, and an anvil, combined with a button conductor or chute, a driver, and a feeding-lever, and with means, substantially as described, actuated by the fastener, to determine when the material shall be fed, whereby should the presentation of a fastener be omitted the material will not be fed, substantially as described.
- 70 13. A swinging frame and a fastener conductor or chute, an anvil, and a driver carried thereby, combined with a button conductor or chute, a feeding-lever, and a presser-foot sup- 75 ported in another part of the frame-work, and with relation to which the said swinging frame and its parts are made movable a greater or less distance, according to the distance to be preserved between adjacent buttons, substantially as described.
- 80 14. In a machine for setting buttons upon boots and shoes and other material, a fastener conductor or chute, a reciprocating driver, op- 85 posite the end of which is placed the fastener to be driven, and a centering device or throat for the point of the fastener, combined with a button conductor or chute, a stop to arrest the undermost button in position opposite the said anvil, substantially as described.
- 85 15. The fastener-receiver, fastener conductor or chute, driver-bar, and driver, combined with a lever connected with the said receiver and driver-bar, and with a movable fulcrum for the said lever, substantially as de- 90 scribed.
- 95 16. In a machine for setting buttons, a fast- 100 ener conductor or chute, grooved to receive the heads and shanks of the fasteners and set at an inclination to enable the said fasteners to descend therein by gravity while resting on their heads, and with their points directed upward, and a transerrer, and driver, and anvil, combined with a button conductor or chute to conduct buttons into position opposite the driver and fastener, the said button conductor or chute being curved and shaped, substan- 105 tially as described, to cause the shank of the button to be turned to present the open eye in the path of movement of the point of the fastener before it meets the said eye, for the pur- 110 poses set forth.
- 115 17. The swinging frame and its driver and fastener conductor or chute and anvil and transerrer and the button conductor or chute, combined with means to enable the material to be fed only after a fastener has been driven, and with a counting mechanism to indicate the number of feeding movements, and con- 120 sequently of the fasteners which are driven, sub- stantially as described.
- 125 18. The button-receiver and button race- 130 way therein, grooved to receive the heads of the buttons when standing on edge, and an agitator to place the buttons in the said race- way, combined with the conductor or chute into which the buttons are discharged from the raceway, the latter at its lower portion having a knife-edged rest for the shank, sub- stantially as described.
- 135 19. In a button-setting machine, a presser- 140 foot and supporting-surface to hold the material, and a driver and anvil to drive a fastener and clinch it about the shank of the button, combined with means, substantially as

described, to change the relative position of the anvil and driver horizontally with relation to the presser-foot, substantially as described.

5. 20. In a button-setting machine, a presser-foot and supporting-surface to hold the material, and a driver and anvil to drive a fastener and clinch it about the shank of the button, combined with means, substantially as described, to change the relative position of the anvil and driver horizontally with relation to

the presser-foot, and with a counter to indicate the number of horizontal movements of the said driver, substantially as described.

In testimony whereof we have signed our names to this specification in the presence of two subscribing witnesses.

LORENZO D. HAWKINS.
ERASTUS WOODWARD.
